UNITED STATES PATENT OFFICE.

PAUL M. KUEHN, OF BALTIMORE, MARYLAND, ASSIGNOR TO THE BARTLETT-HAY-WARD COMPANY, OF BALTIMORE, MARYLAND, A CORPORATION OF MARYLAND.

GAS HOLDER.

Application filed August 28, 1925. Serial No. 53,193.

This invention pertains to gas holders or reservoirs, and more particularly to that type now known in the art as "waterless holders". Such holders are set forth and 5 claimed in U. S. Letters Patent to Konrad Jagschitz, Nos. 1,275,696 and 1,481,099, and the present invention has to deal more particularly with an improved sealing means of the general type set forth and claimed in 10 the last mentioned patent.

Broadly stated, the waterless gas holder may be said to comprise a casing or shell, a piston-like member slidable along the inner surface thereof, such member forming in 15 conjunction with a liquid seal the closure for the holder. In other words, the usual bell and water basin are not present.

The present invention, as above indicated, relates more directly to the means employed 20 for effecting a close contact between the various parts interposed between the edge or periphery of the closure or piston proper and the adjacent faces of the wall elements and to provide means whereby downward 25 flow of the sealing medium is obstructed and restrained.

Where the sealing fluid is relatively thick or viscous, no trouble inheres, but where the sealing fluid is relatively thin, as for instance, tar produced in the manufacture of 30 water gas, it becomes advisable, in fact necessary, that a close union between the movable piston or closure and wall elements be effected to prevent a too free passage of 35 the tar between the closure and the wall of the shell, over which it of course spreads and between the various elements of the sealing structure as such. The arrangement as will hereinafter appear is such that the liquid 40 sealing medium must take a tortuous passage in passing downwardly between the component elements of the rubbing elements. The sealing medium must of course be mobile whether it is relatively thick, or 45 viscous, or relatively thin. Furthermore, means are provided for insuring close contact between the edges of the verticals of the tank structure and the shoes which coat therewith.

50 A structure falling within the scope of the present invention is illustrated in the annexed drawings wherein:

Fig. 1 is a top plan view, of so much of a holder as is necessary to an understanding

of the present invention, parts being shown 55 in section;

Fig. 2 a vertical sectional view taken on the line II—II of Fig. 1;

Fig. 3 a vertical sectional view taken on the line III—III of Fig. 2 looking toward 60 the wall of the holder;

Fig. 4 a transverse vertical sectional view taken on the line IV—IV of Fig. 3;

Fig. 5 a face view, partly broken away, illustrating a portion of the ends of two 65 adjacent rubbing bars or shoes which cooperate with the frame or body of the holder proper;

Fig. 6 a sectional plan view of the adjacent 70 ends of such rubbing bars and body elements;

Fig. 7 a perspective view, partly broken away, of one of the elements or rubbing bars employed in effecting a proper sealing action;

Fig. 8 a similar view of the elements which 75 cooperate with the member shown in Fig. 7, and

Fig. 9 a diagrammatic plan view of a section of the holder.

In the drawings, a portion of the body or 80 shell of the holder is shown, see more particularly Figs. 1 and 9, comprising vertically disposed plates 1 and 2 riveted at their edges to a relatively heavy column or bar like member 3. The inner flat vertically disposed face of the column stands at right angles to the edges of the column, while the outer face is chamfered so that the plates 1 and 2 may extend therefrom at the desired angle in order to produce, by a repetition of 85 said columns and plates, a symmetrical holder, see Fig. 9.

The closure proper, as in the patents above mentioned, is a fabricated structure which extends across and substantially closes the 95 tank or holder and is movable up and down within the holder according to the gas pressure which obtains within the tank beneath the closure. Such a closure is designated by 4, and as shown, has a depending wall 5, a 100 shelf 6, a second depending wall 7 and an outwardly extending circumferential support or bracket element 8, see Fig. 2. As will be seen upon reference to said figure the outer edge of said element stands away from 105 the inner face of the wall of the holder.

As in Patent Number 1,481,099, this structure, together with other elements later de-

scribed, provides a well or trough adapted to contain the sealing liquid, such for instance as tar.

Supported by the closure and urged outwardly against the inner wall of the holder or tank is a series of inter-engaging rubbing shoes or plates and cooperating with the plates is a flexible member which in effect forms the bottom of the trough. As with the plate and column structure, these shoes and the flexible member extend entirely around the closure but only a portion of such elements are shown in detail in the drawings as the parts are mere duplicates, as illustrated in Fig. 9.

Located directly in front of and bearing against each of the columns 3 is a rubbing bar or shoe 9 each end whereof, see Fig. 7, is cut away or notched out at 10, a second and narrower recess of notch 11, extending inwardly from the base of the larger notch or recess. The shoe at each end has secured thereto a pair of blocks, those at one end being designated by 12 and 13, and at the opposite end by 12^a and 13^a.

The blocks are so spaced that they stand close to but not quite in contact with the edges of column 3 so that the shoe may be moved vertically of the column without binding.

Extending between each pair of the column contacting plates are other plates or shoes designated to bear against the inner faces of the plates, as 1 and 2, of the holder. Such plates or shoes are designated generally by 14, and as will be seen upon reference to Fig. 8 the upper and lower edges thereof are preferably inwardly curved. At each end of such plate there is provided a pair of spaced members 15 and 16 formed as an integral portion of the shoe or plate. Secured to said members and to the body of the plate is a filler block 17, the block being wedge-shaped in cross section and provided with two outwardly extending elements 18 and 19 of the same dimensions as the members 15 and 16, to which they are riveted. The opposing faces of the members 18 and 19 are cut away as at 20 and 21, thus providing in conjunction with the extensions 15 and 16 oppositely disposed grooves or ways. The over-all distance between the outer faces of the projections or extensions 18 and 19 is such that said faces make a relatively close contact with the side walls of the opening, or notch 10 into which the extensions 18 and 19 fit when the parts are assembled. Seated within the space formed between the inner faces of the extensions 18 and 19 is a sliding block 22, the block being provided with laterally extending wings or ribs 23, which take into the channels or grooves 20 and 21 and hold the block against lateral displacement with reference to the members 18 and 19 while at

the same time permitting the block to be moved endwise. A spring 24 is seated at one end in a recess formed in the sliding block, the opposite end bearing or rubbing against the adjacent face of the member 17. When the parts are assembled the spring tends to force the block 22 outwardly into the recess 11 formed in the rubbing bar of shoe 9. As will best be seen upon reference to Figs. 6 and 7, the block is of such thickness that it is substantially equal to that of the shoe or plate 9 and the blocks 12 and 13 which are secured thereto. In other words, the forward end, designated by 25, of the block 22 projects outwardly and into contact with the vertically disposed edges of the column 3. The spring tends at all times to hold the face 25 directly in contact with the edge of the column and thus insures a relatively tight joint between the parts under all working conditions.

Preferably, the end 25 of the block, or at least at that portion which contacts the vertically disposed edge of the column, will be rounded, (see Fig. 8) in order that as the shoe or bars are moved up or down, the block will not be cramped or jammed but will be free to be moved inwardly and outwardly owing to the slight inequalities which may exist in the edge of the column, or owing to the slight variations in the measurement of the column at different points in its length.

It is to be understood that this same structure appears at the opposite end of the shoe or bar 14 and that it coats in a like manner with the adjacent end of the next bar or shoe 9 and the column 3 at that point.

In order to maintain a liquid in the trough and to allow the shoes to be urged outwardly into contact with the columns and the plates, I preferably employ a flexible member as 26, formed of canvas or equivalent material. The inner edge of this material is clamped between an upstanding angle 27 secured to the member 8 and a plate 28 attached by bolts or the like to the member 27. The canvas is doubled upon itself and the folded portion bears against the rubbing shoes or plates and also the filler blocks 17 and is clamped against said elements by suitable plates as 29, 30 and 31. (See more particularly Fig. 6).

As will be seen upon reference to Figs. 2 and 4 the canvas is carried down and around bars 32 preferably of wood and the edge 26^a is stitched to the body. These bars act as spacers and serve to hold the canvas out of contact with the wall of the holder and to thus prevent wearing of the canvas against the wall as the closure or piston is moved up and down. Suitable wooden elements, 32^a, (see Fig. 2), form a rest for the lower portion of the canvas and hold such portion out of contact with metal which would have a tendency to chafe it.

As will be seen upon reference to Figure 3, the flexible element 26 is formed with plait or folds 26^b where the ends of the rigid pressure transmitting elements approach each other.

By reason of the construction above outlined, there is produced an expansible or dilatable trough or channel, the lower portion whereof is flexible, and which extends entirely around the structure between the inner face of the wall and the outer portion of the piston or closure proper. As above indicated and as shown in Fig. 2, this trough is designed to be filled with a liquid sealing medium, such for instance as tar. To prevent the sealing medium from running around to one side, should the closure assume a position other than horizontal, the channel is divided into a series of pockets. This is accomplished by securing the lower ends of vertically disposed strips 33 and 34 of canvas, (see Figs. 1 and 3), to the canvas element 26, and securing the vertically disposed edges thereof to upward extensions 9^a 25 of shoes 9, and to a vertically disposed element 35 secured to the closure, or more specifically to frame elements 36 and 37 secured to the closure.

It is of course essential that the various rubbing shoes or pressure elements or members be held in close contact at all times with the plates 1 and 2 and the columns 3. Any suitable means may be employed to effect this object but the arrangement shown is preferred. It may be said, to comprise a series of weighted levers, the lower, shorter ends whereof are interconnected with the rubbing elements and tend at all times to force them outwardly into face-wise contact with the columns and plates. The parts, which may be denominated means for pressing the pressure members or elements against the shell, are duplicated around the structure, hence, a description of one will suffice.

Secured to element 6 of the closure is a pair of angle bars 38 and 39 each upstanding element thereof having two longitudinally disposed slots formed therein. Adjustably secured to said elements is a pair of arms 40 and 41 the outer ends whereof, (see Fig. 2), extend downwardly. A shaft or bar 42 is mounted in said ends and forms the bearing for a sleeve or hub 43 having formed integral therewith, or secured thereto, a pair of diverging arms 44 and 45. The upwardly extending arm 44 has secured to it a weight 46 while the lower arm 45 is provided with an opening through which extends a pin 47. Pin 47 finds its bearings in bracket pieces 48 and 49 secured respectively, to the rubbing bar or shoe 9 and the intermediate shoe or rubbing bar 14. Spacer blocks 50 and 51 are placed upon pin 47 between the brackets and arm 45. A rod 52 is secured

in arm 45, the ends of the rod extending through arcuate slots as 53, (Figs. 2 and 4) formed in the brackets. This arrangement forms limit stops for the weighted lever. As will be noted, the weighted lever is connected to and coacts with the rubbing shoes adjacent the ends thereof, hence, any tendency to spring is obviated and the shoes are held closely to the wall. The tar of course seals the joint and at the same time lubricates the surfaces.

As above noted, blocks 22 are constantly pressed against the edges of the columns and by reason of the construction of the ends of the shoes as above set forth, downward flow of the sealing medium is materially obstructed. The end construction of the shoes may be said to produce a labyrinth packing and the ends may be said to have a dental engagement. The flexibility of the connections between the parts enables the shoes to properly seat themselves and, moreover, by reason of the construction above described, no strain is placed upon the canvas, no sharp bends being present therein as it passes from one shoe to another.

In other words the projecting members 18 and 19 and the recessed or notched end of the elements 9, together with the interposed block 22 produce a dental engagement or connection between the rubbing elements or shoes which, while insuring engagement, produces a flexible or yielding connection and insures functioning of the parts with the wall of the holder under all conditions.

Stated in another way, the interconnected series of shoes 9 and 14 may be said to form a flexible sealing element or dilatable annulus extending entirely about the movable closure.

Hence the interconnected members 9 and 14 may be said to produce a dilatable annulus of pressure members joined in series by flexible joints that permit expanding and contracting distortion of such annulus and are substantially leakage-proof, combined with the pressure exerting means, such as the supporting brackets 48, 49; sleeve 43; arms 44, 45; and weights 46 placed about the closure, as best indicated in Figure 9, and acting severally toward the inner surface of the holder to maintain between said surface and the outermost peripheral surface of the closure or piston structure such working contact as to keep in substantially gas-tight relation with said surfaces a mobile medium supplied to and adapted to spread between them as the piston rises and falls.

What is claimed is:

1. In a gas holder of the waterless type, the combination of a shell or casing; a movable closure located within the same, said closure having a plurality of rubbing shoes bearing against the inner face of the casing, said shoes at their ends having a dental en-

gagement; and means for retaining a liquid sealing medium above said shoes.

2. In a gas holder of the waterless type, the combination of a shell or casing; a movable closure located within the same, said closure carrying a plurality of rubbing shoes bearing against the inner face of the casing, said shoes having interfitting recesses and projections at their ends; and means for retaining a liquid sealing medium above the shoes.

3. In a gas holder of the waterless type, the combination of a shell or casing; a movable closure located within the same; a plurality of rubbing shoes carried by the closure and bearing against the inner face of the casing; a labyrinth packing formed between the adjacent ends of the shoes; and means for retaining a liquid sealing medium above said shoes.

4. In a gas holder of the waterless type, the combination of a shell or casing; a movable closure located within the same; a plurality of rubbing shoes carried by the closure, said shoes bearing against the inner surface of the casing, said shoes at their adjacent ends being in interengagement; means located at such point of connection for preventing down flow of a sealing medium between the shoes and the casing; and means for retaining a liquid sealing medium above the shoes.

5. In a gas holder of the waterless type, the combination of a shell composed of a series of vertically disposed columns and a series of connecting plates; a movable closure located within the same; a plurality of rubbing shoes carried by the closure; means for urging said shoes outwardly into contact with the shell; and means carried by the shoes acting upon the edges of the columns to effect a tight joint therewith.

6. In a gas holder of the waterless type, the combination of a shell or casing composed of a series of vertically disposed columns and a series of interconnecting plates, the edges of the columns being exposed within the casing; a movable closure; a plurality of rubbing shoes movable with the closure; means for urging the same outwardly into contact with the wall of the casing; and spring-pressed means carried by the shoes adjacent the columns, said means acting upon the edges of the columns and making a tight fit therewith.

7. In a gas holder of the waterless type, the combination of a shell composed of a series of vertically disposed columns and interconnecting plates, the edges of the columns being exposed within the confines of the casing; a movable closure located within the casing; a series of shoes supported from the closure and extending around the same, the ends of the shoes being in interengagement; a block carried by the

shoes adjacent their ends, said block standing in line with the exposed edges of the columns; and means for forcing said blocks outwardly into contact with said edges.

8. In a gas holder of the waterless type, the combination of a shell composed of a series of vertically disposed columns and interconnecting plates, the edges of the columns being exposed within the confines of the casing; a movable closure located within the casing; a series of shoes located about the margin of the closure; means for urging said shoes outwardly into facewise contact with the columns and plates; and yielding means carried by the shoes adjacent the columns and contacting the edges thereof to effect a tight joint therewith.

9. In a gas holder of the waterless type, the combination of a shell composed of a series of vertically disposed columns and interconnecting plates, the edges of the columns being exposed within the confines of the casing; a movable closure located within the casing; a series of shoes located about the margin of the closure; means for urging said shoes outwardly into facewise contact with the columns and plates; and sliding blocks mounted in the shoes adjacent the edges of the columns, said shoes bearing against such edges and making a tight joint therewith.

10. In a gas holder of the waterless type, the combination of a shell or casing composed of a series of vertically disposed columns and interconnecting plates; a movable closure located within the casing; a series of shoes extending around the marginal portion of the closure, the ends of the shoes being in interengagement; means for urging the shoes outwardly into facewise contact with the columns and plates; a sliding block mounted at the juncture of the shoes adjacent each edge of each column; means for urging said block endwise against the adjacent edge of the column; and means for retaining a liquid sealing medium above the shoes to prevent the escape of gas.

11. In a gas holder of the waterless type, the combination of a shell or casing composed of a series of vertically disposed columns and a series of interconnecting plates; a movable closure mounted within the casing; a series of shoes bearing against the plates and columns, the ends of the shoes having an interdental connection; a sliding block mounted upon the shoes at the joint thereof adjacent the edges of the columns; means for urging said block endwise against the adjacent edge of the column, means for urging the shoes outwardly into facewise contact with the columns and plates; and a flexible member extending from the shoes to a fixed portion of the closure, said flexible member forming with the closure and the wall of the casing a trough for the reception

of a liquid sealing medium to prevent the escape of gas.

12. In a gas holder of the waterless type, the combination of a shell or casing embodying vertically disposed columns; a movable closure mounted therein; a series of shoes extending around the closure and adapted to make a sealing contact with the inner face of the casing; a labyrinth packing formed between the ends of the adjacent shoes and embodying an endwise movable member which bears against the adjacent edge of the column; and means for urging said member into contact with the column to prevent the escape of gas.

13. In a gas holder of the waterless type, the combination of a shell or casing embodying a series of vertically disposed columns and interconnecting plates, the edges of the columns being exposed within the casing; a movable closure; a shoe bearing against the innermost face of each column; intermediate shoes bridging the space between the columns and bearing against the inner face of the plates; interdental connections between the adjacent ends of the shoes; a sliding block located at the joint between the shoes adjacent each column edge; means for urging said block endwise into contact with the adjacent edge of the column; means for forcing said shoes outwardly into contact with the shell of the casing; and means, embodying a flexible element, forming a trough for a liquid sealing medium between the edge of the closure and the inner face of the casing to prevent the escape of gas.

14. In a gas holder of the waterless type, the combination of a shell or casing comprising a series of vertically disposed columns and interconnecting plates, the edges of the columns being exposed within the casing; a movable closure mounted therein; a shoe bearing against each of said columns, the shoes being provided with projections which extend inwardly adjacent the edges of the columns; a series of intermediate shoes adapted to bear against the inner face of the plates; a filler member secured to the inner faces of such intermediate shoes adjacent each end thereof, said filler member being provided with endwise projecting elements adapted to enter a recess formed in the adjacent end of the shoe which bears upon the column; a sliding block mounted between the projections aforesaid; means for urging said block outwardly and into contact with the adjacent edge of the column; means for urging said shoes outwardly into facewise contact with the columns and plates; and means for retaining a liquid sealing medium around the periphery of the closure and at a point above the shoes to prevent the escape of gas.

15. In a gas holder of the waterless type,

the combination of a shell or casing embodying in its structure vertically disposed columns the edges whereof are exposed within the casing; a movable closure located within the casing; a plurality of shoes carried by the closure; means for forcing the same outwardly into facewise contact with the inner face of the casing; and yielding means, carried by the shoes, contacting the edges of the columns to prevent the escape of gas.

16. In a gas holder of the waterless type, the combination of a shell or casing; a closure mounted for vertical movement within the casing and having an attaching flange adjacent its periphery; a substantially continuous series of shoes surrounding said closure and adapted to enter into sealing contact with said casing around the periphery of said closure; yielding means serving to urge said shoes into contact with said casing; a flexible member extending from the shoes to said attaching flange; and releasable means for clamping said flexible member to said flange.

17. In a gas holder of the waterless type, the combination of a shell or casing; a movable closure located within the same; a plurality of rubbing shoes bearing against the inner face of the casing, said shoes at their adjacent ends being flexibly interconnected and thereby forming in effect a continuous rubbing element; means acting upon the shoes urging them into contact with the wall of the holder; and means for maintaining a sealing fluid between said shoes and the inner wall of the holder.

18. In a gas holder of the waterless type, the combination of a shell or casing; a movable closure located within the same; a substantially continuous flexible rubbing element extending around the edge of the closure comprising a plurality of flexibly interconnected members and contacting the inner face of the wall of the shell; means acting upon said element to force the same outwardly into close contact with the said face; and means for maintaining a sealing fluid between said element and the inner wall of the holder.

19. In a gas-holder of the piston-closure type, in combination: a shell or holder and, vertically movable therein, a piston-closure structure peripherally including, in flexible gas-tight connection with its inner portion, an annulus of pressure members joined in series by flexible joints that permit expanding and contracting distortion of such annulus and are substantially leakage-proof; means for constantly pressing said pressure members severally toward the inner surface of said shell or holder, to maintain between said shell or holder surface and the outermost peripheral surface of the piston-closure structure such working contact as to

keep in substantially gas-tight relation with said surfaces a mobile medium supplied to and adapted to spread between them as the piston-closure structure rises and lowers; and means for supplying such mobile medium to said working surfaces.

20. In a gas-holder of the waterless type, the combination of a shell or casing; a movable closure located within the same; a plurality of rigid members extending around the periphery of said closure; means flexibly interconnecting the ends of said members whereby a dilatable annulus is formed; means for severally applying pressure to said rigid elements to force the same outwardly toward the inner surface of the shell;

and means for effecting a gas seal intermediate the shell and the annulus.

21. In a gas holder of the waterless type, the combination of a shell or casing, a closure therefor comprising in combination a body element; a dilatable annulus surrounding and supported by the same, said annulus comprising a series of substantially unyielding elements flexibly interconnected throughout the series at their ends to thereby permit of outward dilation; and means severally acting upon said elements to dilate the annulus.

In testimony whereof I have signed my name to this specification.

PAUL M. KUEHN.
